FINGER-WEIGHT ARTERY COMPRESSOR

John Nugent Walters, New York, N. Y.

Application July 12, 1945, Serial No. 604,573

2 Claims. (Cl. 128—327)

1

This invention relates to the new and novel construction and improvement in tourniquet type constrictors, and aims to provide a new and novel apparatus of peculiar structure, so designed on novel principles that only "finger-weight" pressure, applied to an arterial pressure-point, is sufficient to control the circulation of blood through the limbs or extremities, thus to prevent bleeding to death, to administer intravenous blood transfusion or infusions of blood plasma; this invention is designed, further, to eliminate the hazard of gangrene debridements and amputations heretofore consequent and attributable to the barbaric practice of applying forcible and prolonged tourniquet constriction to casualties involving artery-severed wounds; and, this invention, furthermore, is so designed and conceived to enable any aid-isolated casualty victim to effectively, positively and safely prevent bleeding to death, to easily and simply affix the novel apparatus with either hand, and to entirely perform the functions of manipulation and regulation thereof, all without any assistance, until competent aid arrives to take over. This invention, moreover, comprises a novel combination and arrangement of readily obtained or constructed constituent elements, materials and parts to be assembled as directed into one reciprocally operating unit, by means of which to accomplish the purposes intended. No other apparatus heretofore on the market or known to the inventor is so feasibly and positively self-applicable, or so fully conducive to positive self-manipulation, self-regulation and/or self-sustentation, or so instantly and positively adjustable to intermittently and positively retard or regulate the gushing of blood to any determined or necessary degree, or to completely stop the hemorrhage for any determined period of time, all without any outside assistance.

Tourniquets as heretofore constructed and utilized are not conducive to self-application and self-regulation by panicky "blood-gushing" casualty victims; such previously employed tourniquets are of doubtful value and always a source of danger to aid-isolated combatants and war-zone casualty victims, and especially dangerous in the event of syncope.

During World War II thousands of unattended combatants and civilians have died needlessly from arterial wounds suffered under and during bombardment, solely because of unchecked hemorrhage. Many additional thousands have too often been needlessly subjected to amputations, solely attributable to gangrene infections of limbs and extremities resulting from necrosis and mortification of the blood-starved flesh, tissue

2

and bone structures, all primarily induced by the total constriction forcibly applied by means of improvised or other barbaric types of tourniquets heretofore utilized; said total constriction completely shut off circulation of the nourishing and protective blood supply beyond the constricting instrument, thus causing withering mortification and gangrene of the extremities, and consequent surgical removal.

First aid instructions issued to United States Armed Forces recommend and prescribe improvisation of a tourniquet from a "general issue" belt or sock, which must then be excruciatingly twisted tight with a bayonet scabbard. Other human aid is seldom at hand when combatants fall wounded; a "blood-gushing" casualty victim under fire is not able to construct, apply and manipulate such an improvised tourniquet, even if the materials are readily available. Combatant soldiers, particularly, are usually "on their own" under bombardment, and too often remain where they have fallen wounded, alone for many hours until the Medical Corps arrives to find them either needlessly dead, beyond recovery from loss of blood, or subjects for amputation because a Samaritan comrade hastily improvised an immobile tourniquet.

All tourniquets heretofore known and available on the market have been designed, constructed and manufactured to function on the activating principle of "total constriction" of the circulation, barbarically and forcibly applied to an extremity and concentrated at a point between the heart and the severed artery. Said total constriction was accomplished by (1) employing clamps or forceps to "squeeze" the affected extremities or to seal off the exposed arteries by direct application, and usually held in place by an aide or by means of springs, ratchets, or other contrivances; (2) affixing a strap and pulling it taut until the bleeding stopped, and usually held in fixed constriction by means of an attached buckle, or other contrivance; (3) improvising from straps, ropes, belts or any other workable material at hand which were affixed and twisted with a stick until the bleeding stopped, and usually held in fixed constriction manually, or by means of any contrivance available and suitable. If an aide was not present, if materials were not available, the victim usually bled to death before help arrived.

Important new factors feature and distinguish this new and novel invention. It will be perceived that said invention is of pocket size, instantly available, and ready for use in any emergency requiring tourniquet treatment; that it is easily self-

applied, easily self-regulated and easily self-controlled to any determined degree for any determined period of time, by any aid-isolated casualty victim, all entirely without any assistance; that it substantially embodies principles heretofore non-existent, but essential as a safety factor, to prevent and eliminate necrosis and mortification of flesh, tissue and bone structures by making possible the application of controllable "spot" pressure focalized at an exact point in just sufficient degree to regulate or control the bleeding, and without harmfully "over-constricting" or stopping the circulation of blood through unaffected but surrounding capillaries and blood-vessels; that it assures an aid-isolated casualty victim of a safe apparatus to control blood circulation; and, that it provides a convenient and positive circulation control for intravenous blood transfusions, and blood plasma infusions. Thus my invention not only saves lives, it also saves limbs and extremities which might otherwise require amputation by reason of harmful "over-constriction" and/or necrosis of corollary but uninjured blood-vessels, fleshy tissues and/or bone structures.

It is within the province of my instant invention (1) to advance the utility and value of devices of the type to which this invention appertains, (2) to greatly improve over the usefulness and results given by other contrivances of similar purpose, (3) to simplify and assure the adequate control of hemorrhage from the extremities caused by artery-severed wounds, (4) to preserve and extend the usefulness of limbs and lives indefinitely, (5) to control the flow of blood during transfusion, and (6) to regulate the administration of blood plasma into the circulatory system.

My instant novel invention is so constructed, arranged, conceived and designed in order to employ and utilize the manually actuated principle of leverage and counter-leverage to adequately generate sufficient controllable power with which to direct, focalize and/or maintain positive but releasable compression to a selective arterial pressure-point, and by means of which to retard, regulate, completely stop or otherwise control the circulation of blood in any limb or extremity, and to any desired degree for any desired period of time; said invention, further, is so compact and adjustable and practical, so easy to carry and utilize, so simple to self-affix and self-manipulate and self-regulate, and, so simple and inexpensive to construct, that a general issuance thereof to all United States Armed Forces is warranted.

General issue of my instant invention to United States Armed Forces, furthermore, would bring about the conservation of our limited supplies of blood plasma and precious whole blood, heretofore necessarily administered to casualty victims who have lost great quantities of blood; blood-bank stocks would thus be released for and become available to the most grievously wounded. Additional embodiments and humane benefits which would inure to our fighting men may be here mentioned as (1) the relief or entire elimination of the excruciating pain attending employment of tourniquet procedures and the twisting to unbearable constriction as heretofore practiced, and (2) the greatly increased probability of appropriate rehabilitative treatment to restore function and utility to limbs and extremities damaged by arterial wounds, but which heretofore became complicated because of "over-constriction."

My instant invention, for the foregoing and other self-apparent reasons, should be included

as a standard unit in every combatant's personal casualty kit, as an essential to the conservation and preservation of valuable lives and limbs for future usefulness to humanity; and this invention, furthermore, should likewise be included in the casualty kits of every Medical Corps field aide, and also provided as an essential component of the equipment furnished to every casualty depot, and in every field and base hospital of our armed forces.

It is the principal object of this invention to provide an inexpensive artery compressor of novel structure conceived and designed for self-use, and employing the novel and peculiar principle of "controllable pressure" so that only a "finger-weight" is sufficient to positively and adequately control hemorrhage from arterial wounds, and to thus eliminate the dangers of necrosis and mortification heretofore primarily caused by barbaric, gangrene-inducing tourniquets which aid-isolated casualty victims could not by themselves apply or control, and, to thus eliminate the hazard of consequent and subsequent amputations; in place of said hazardous tourniquets, my instant invention provides a novel and practical "finger-weight artery compressor" for self-use which is adequate for any emergency, which is safe and efficient to the highest degree, and which is minute enough to occupy only two loops of a regulation cartridge-belt, quickly available and easily detachable, ready, and simple enough to be instantly affixed, applied, manipulated and regulated by any aid-isolated casualty victim, and all without any assistance.

With the above and other valuable features, objects and embodiments in view, which will become apparent and obvious as the description proceeds, this invention resides in the peculiar construction of the elements, the preparation and processing of the parts involved, and the arrangement and assembly thereof, by means of which to produce controllable power through leverage and counter-leverage action, and the application of which, within the intent, spirit and scope of what is claimed and in accordance with the principles of my instant invention, consists in the following exemplified steps and operations, all as described and claimed.

Processing and assembling the elements and parts

In order to illustrate the character and physical structure of my novel artery compressor which requires only a "finger-weight" of pressure and aims thereby, in accordance with the principles of this invention, to eliminate the hazards of necrosis and mortification, and the incident gangrene debridements and consequent amputations, the accompanying drawings are furnished, in which:

Figure 1 denotes a strap, an incidental but corollary compression element common to all tourniquets but which, here, provides only a collaborative function incidental to the application of desirable "finger-weight" pressure; in accordance with the principles of my instant invention said strap furnishes sufficient binding support evenly all around the limb, the primary source of power to achieve the desired amount of compression is attained by a manually actuated reciprocal leverage action; the strap is loosely applied to an injured limb or extremity and then tightened to any desired degree by a reciprocal reaction induced by a manual actuation which, as will be shown, makes possible the self-regulation and

control of blood circulation by any aid-isolated

casualty victim, without any assistance. As here shown said strap is initially cut and processed from a strip of leather to a length suitable to fit an arm or leg or other extremity to which a tourniquet may be physically applicable.

Figure 2 denotes a buckle, an incidental but corollary controlling element, but which, here, provides the means by which to adjust the length of the strap (Figure 1) to any suitable or required size, and also to furnish an auxiliary and alternative means by which to regulate the degree of compression desired to eliminate needless "over-constriction" of an extremity to which my artery compressor is affixed. As here shown said buckle is of the type commonly known as a "gripper slide buckle" and is riveted to one end of the strap, as illustrated in Figure 2 at a.

Figure 3 denotes a compressor, the primary pressure element of my invention and which is claimed herein, by means of which to apply "focalized" spot pressure to a specific arterial pressure-point, which may be regulated in accordance with the principles of this invention to any degree of compression required to effectually control hemorrhage; in contrast to heretofore practiced barbaric and dangerous "total constriction," only a "finger-weight" of pressure exerted on the compressor is sufficient; thus, applied and controlled without any assistance, the hazard of "over-constriction" is eliminated, as well as the consequent necrosis and mortification of surrounding blood-vessels, capillaries, flesh tissues and bone structures. As here shown said compressor is initially processed from a block of wood to the shape of a "cylinder" as illustrated c with an extending "lever" as illustrated b in Figure 3.

Figure 4 denotes a lock, the fastening and sustaining element of my invention and which is claimed herein, by means of which to accomplish and automatically maintain controllable compression which is fixable and/or adjustable to any degree in accordance with the principles involved therein; said compression may be likewise instantly and wholly released by a simple reverse manipulation. As here shown said lock is initially processed from forged steel to a suitable size and shape as illustrated; the lever of the compressor (Figure 3,b) is depressed into and held in thus fixed stress by the "loop" of the lock which is identified at d in Figure 4; the stapling-sharpened end of the lock is intended to be permanently attached to the strap, having been sharpened for that purpose as at e in Figure 4.

Figure 5 denotes one of a plurality of nails, incidental but corollary elements, of common usage, but which, here, are employed in sufficient quantity to permanently fasten together the compressor (Figure 3) and the strap (Figure 1) into one cooperating and collaborating unit which, under manual actuation of the lever of the compressor (Figure 3,b) and thus in accordance with the principles of my invention, becomes a "fulcrum" for reciprocal leverage action by means of which the strap is tightened; adequate power and compression is thus produced by means of which to accomplish the aims and purposes of my invention in accordance with the principles thereof. As here shown said nails are of the type commonly used by carpenters etc.

Figure 6 denotes a detail to illustrate the manner of attaching the lock 4 by clamping the sharpened end e to the strap 1 at a point approximately midway between the buckle 2 and the compressor 3 to make one reciprocally acting co-

operative unit of both the lock and the strap; with an uninjured hand, the lever b is manually depressed under and guided into the loop d and thus locked, without any assistance, for any desired period of time until voluntarily released; both hands are thus left free for other emergency needs.

Figure 7 denotes a detail to illustrate the employment of a plurality of nails 5 to attach the strap 1 to the lower peripheral center of the compressor cylinder 3c at a point approximately four inches distant from the attached end of the buckle 2; this point becomes the "fulcrum" for the reciprocal "leverage" action produced upon manually depressing the lever 3b and thus causing the strap 1 to tighten for the purpose of achieving compression in accordance with the principles of my invention, and which may be sustained at any degree merely by engaging the lever 3b by the lock 4.

Figure 8 denotes a detail to illustrate the approximate point at which to attach the compressor cylinder 3c to the strap 1 and the manner of joining both into one collaborative unit by means of the plurality of nails 5.

Figure 9 denotes a detail of the completed "finger-weight artery compressor" as it appears when all of the corollary, constituent, component, cooperative, collaborative and reciprocal elements, materials and parts have been processed, arranged and assembled into one integral unit. As here shown my invention comprises the strap 1 to one end of which the buckle 2 has been riveted (2a) and both ends of the strap buckled together; the lock 4 has been stapled to the strap and the compressor 3 likewise permanently attached by employing the plurality of nails 5; all as related together in combination and integral assembly thereof. The lever 3b has been slipped into the loop of the lock 4d to be thus automatically held until voluntarily released. My instant invention is thus ready to be quickly affixed to a wounded extremity, and is fully adjustable in accordance with the principles involved to any degree of controllable compression, as well as the complete release thereof at will, and all entirely without any assistance.

Controlling hemorrhage by "finger-weight" arterial compression

In order to illustrate the character, the steps, the operations, and the methods of preparation involved in the physical application, regulation and manipulation of my novel "finger-weight" artery compressor to control hemorrhage, and to eliminate the hazards of necrosis and mortification, the accompanying drawings are furnished, in which:

Figure 10 denotes a perspective of the completely assembled "finger-weight artery compressor" buckled to make one continuous loop and thus ready to be loosely affixed over the arm or leg, or any other anatomical extremity to which a tourniquet may be physically applicable. As here shown the compressor 3 has been left free but may be slipped into the lock 4 before the strap 1 has been affixed to the extremity to be treated; the desired degree of compression may be achieved by finger-manipulation of the slide 70 of the buckle 2 which lengthens or shortens the circumference of the strap 1 and thus either tightens or loosens the strap to any degree desired, depending upon which direction in which activated. In accordance with the principles involved in my invention, any aid-isolated victim

may completely perform the functions and purposes thereof, without any assistance.

Figure 11 denotes a perspective which serves to illustrate the minute dimensions into which my "finger-weight artery compressor" may be rolled up, and into a compact "kit" small enough to fit into the space occupied by only two cartridge loops of a field service belt. As here shown the lever of the compressor had been slipped into the loop of the lock; the strap was then pressed parallel to the lever and rolled lengthwise completely around the compressor; a rubber-band, or a slide-clip, or any other contrivance may be utilized to hold the kit in a compact. By "pre-adjusting" the length of the strap beforehand my instant invention is ready to be "unrolled" with one hand and immediately slipped onto any involved extremity; gravity will do the "unrolling" if the loose end of the strap is grasped. The entire "kit" may then be clipped to the cartridge-belt for easy detachment, or carried in any other manner providing instant availability; it is thus ready to be self-affixed and self-manipulated without any assistance, and is fully capable of furnishing compression instantaneously when utilized in any emergency requiring tourniquet treatment.

Figure 12 denotes a transparency which serves to illustrate one of the various possible embodiments, characteristics and functions of my "finger-weight artery compressor." The drawing represents a transparency of a human arm in which an artery has been severed and the need for tourniquet treatment thus indicated; the lever of the compressor element has been slipped into the lock, the cylinder has been affixed directly over the main artery at a known pressure point, and is thus sustained at a hypothetically proper degree of compression; just sufficient pressure has been applied to retard and control the flow of blood through the artery, at the same time allowing a sufficiency of blood to circulate through unaffected veins and capillaries to provide nourishment to other parts of the wounded extremity; thus obviating, in accordance with the principles of my invention, the hazards of necrosis and mortification usually following heretofore practiced tourniquet procedures based upon total constriction, which too often necessitated subsequent major gangrene debridements actually tantamount to amputations. As here shown in transparency, the letter F in the drawing represents the main artery and the letter G the veins, as they are assumed to appear during full and normal circulation. In the drawing my instant invention has been applied just below the elbow, actuated, fixed and functioning to retard the blood circulation; below the said focal point of compression, the main artery has ceased flowing and is thus to be construed in the illustration which is represented by the letter f; the letter g on the other hand indicates that circulation continues to flow through surrounding uninjured veins and capillaries, in reduced quantity but yet sufficient to provide continuing nourishment which reduces or completely eliminates mortification of the unaffected parts of the wounded extremity. Only a "finger-weight" of compression focalized at a specific arterial pressure-point is sufficient to control the circulation of blood through the main artery, represented by the letters F—f, which thus obviates the danger of necrosis at the point of compression. In the drawing, the letter H represents the hypothetical

wound; and the letter J represents the point at which the artery F—f has been severed.

Figure 13 serves to illustrate that only the pressure of a "finger," when focalized over an arterial pressure-point, is sufficient to stop the blood circulation. As here shown the letter K represents a "finger" functioning to stop and control the circulation of the blood through the main artery F and the veins G.

Figure 14 serves to illustrate by way of contrasts to Figure 13, how all heretofore practiced tourniquet procedures "squeezed" the entire extremity to a "pulp" at the point to which applied, thus imposing necrosive "total constriction" which completely stopped all circulation of the blood; such tourniquet procedures too often resulted in complete mortification of the entire un-nourished extremity thus necessitating gangrene debridements, and subsequent amputation. As here shown by way of contrast to Figure 13, it becomes wholly obvious and apparent that my instant invention is capable of regulation, in accordance with the principles involved, to impart only a "finger-weight" of pressure to a focalized and specific spot and to thereby obviate the "total constriction" heretofore employed in the previously practiced tourniquet procedures. In the drawing, the letter L represents a tourniquet representative of the types heretofore employed, all of which were basically dependent upon "total constriction" to stop circulation of the blood; the letter M is intended to represent how terribly excruciating and barbaric is the "total constriction" of an extremity, the results of which too often require amputation due to the necrosis and mortification of "squeezed" tissues, flesh and the bone structures as well.

The foregoing specifications completely describe the preparation, construction, arrangement and assembly of the constituent and component elements, materials and parts, and the integral relation of each thereof to complete the whole thereof, and illustrate the methods of application and manipulation of my novel "finger-weight artery compressor," all as involved, embraced and embodied therein in accordance with the principles of my instant invention. Corresponding identifying characters have been employed in the foregoing views to indicate the various parts and references thereto in the text of the descriptions thereof. Anyone who is able to read should likewise be thereby enabled to easily follow these simplified directions and to safety, effectively and positively control hemorrhage caused by arterial wounds until such time as competent aides arrive and/or hospitalization can be provided, all entirely without any assistance in the utilization of my instant invention.

Medical authorities recommend the release of tourniquets every 20 minutes to permit blood nourishment to circulate to all parts of a wounded extremity. In employing my instant invention as a tourniquet the compression produced thereby may be released instantly and at will; a simple side-wise finger-flicking action will unlock the lever of the compressor, thereby effecting complete release of all pressure; a partial release of pressure may be instantly achieved by a simple "fingers and palm" technique of manipulation which will loosen the moveable tension-slide of the buckle. To resume full pressure it is only necessary to again depress the lever of the compressor and flick it back into the lock; pressure may be adjusted to any desired or required degree of compression by simply sliding back the buckle

to tighten the strap; sliding the buckle in one direction "tightens" the strap, and in the opposite direction "loosens" the strap.

Let it now be supposed that a casualty has occurred. For instance, let it be assumed that a soldier has been struck by flying bomb-fragments, or perhaps a bayonet thrust in combat has cut into his forearm; an artery has been completely severed, a large wound is gaping wide open, and life-blood is gushing away. Under such circumstances the wounded soldier may be under steady bombardment for many hours, perhaps for days.

On the battlefield, in the event of personal casualty it is "every man for himself" and a wounded soldier can hardly do more than to seek shelter in "no-man's land," then pray for status quo perhaps, in a "fox-hole." Let us further assume that the hypothetically described "wounded soldier" has been able to control the blood-gushing while "on the run" perhaps by compressing the artery with the fingers of his "free" hand. Tourniquet application is definitely required.

Having previously been instructed to prepare and buckle together both ends of the strap, the moment temporary shelter has been reached the "soldier" unclips his "general-issue" finger-weight artery compressor, takes hold of the loose end of the strap and allows gravity to unwind the "kit-rolled" apparatus. He now slips the loop of the strap onto the wounded arm; holding the loose end of the buckled strap with the "palm" of the "free" hand, and the tension-slide buckle with the "fingers," a simple and easy "fingers and palm" manipulation will adjust the circumference of the strap to permit of sliding and guiding the cylinder of the compressor past the "wound" and to thus locate the compressor onto a known arterial pressure-point. The "fingers and palm" technique is now employed to manipulate the tension-slide of the buckle until the strap is tightened to a "loose" fit; by manually depressing the lever of the compressor down and into the lock, the circulation of blood will be under his complete control; any degree of compression is now possible, merely by tightening or loosening the strap by means of the tension-slide action of the buckle. My "finger-weight artery compressor" thus affixed over the artery and locked at the proper degree of compression will remain in automatic fixed compression, and may be as easily and readily self-released every 20 minutes until competent or professional aid arrives. Arterial "pressure-points" are known to all soldiers and Medical Corps aides through first aid training courses and casualty manuals.

While my instant invention is adapted to adequately serve the purposes and to perform the functions for which it is intended, it should be understood and I wish to point out specifically that various possible changes might be made in the embodiments, methods of preparation, and in the applications and/or manipulations thereof, without departing from the spirit and scope of my instant invention. It will be obvious for instance, that many other materials may be found and utilized which might be equally suitable and adaptable and to function as well; and also, that other uses and purposes might present themselves. I am likewise aware that many other constructions, combinations, arrangements and assemblies of the embodying elements and principles of my invention could be designed with in the intent, spirit and scope of what is claimed, and substituted therefor, by those learned and

skilled in the constructions and applications thereof, solely to evade the scope of my claims and rights thereto.

Therefore, it is to be understood that the embodying principles of my instant invention as a whole, and all matter contained in the foregoing descriptions and disclosure or illustrated in the accompanying drawings, are intended to be interpreted as illustrative and not to be limited in any sense to the exact or precise forms of execution set forth, nor to the precise and exact embodiments, materials, processing, construction, combination, arrangement and assembly of the component and integral elements and parts disclosed and described, nor to the precise and exact methods of preparation, application and manipulation thereof, nor to the exact and precise sequence of steps and procedures involved.

On the contrary, I deem my invention to include and embrace the peculiar structure of my novel finger-weight artery compressor per se, and all of the foregoing described and disclosed embodiments, methods of construction, applications and techniques therein contained, and the utilization and manipulation thereof, as well as all possible variations of the same, and any changes which may suggest themselves solely for purposes of infringement of my rights thereto and the evasion of my specific claims. I also deem my invention to include and embrace any and all suitable materials which will lend themselves readily to the requirements of the character, structure and principles involved without departing from the spirit and scope thereof, for the purposes intended; and also, that any or all of the component elements and parts disclosed and described may be prepared and processed by any means or method whatsoever without departing from the spirit and scope of my invention, and to any blank, form or shape of any gauge, size, length, width, breadth, circumference or diameter, and/or cut, molded, cast or formed, and employing any combinations thereof whatsoever may be constructed, manufactured, arranged, glued, fused, riveted, welded, screwed, stapled, sewed, attached, assembled and/or applied and actuated in any sequence of steps or order of procedure by any method or in any manner whatsoever. Likewise, I deem my invention to embrace and include any and all contrivances and objects of whatever nature which will contribute to the requirements and principles involved, the scope of which will be indicated in the claims which follow, and which may be employed or substituted in place of the illustrative embodiments herein disclosed to achieve the aims, intents and purposes of my invention.

Having thus described my novel invention, I hereby apply for the full protection of my rights, interest and title in and to the said invention, and to the exclusive ownership thereof under the security of United States Letters Patent for the full term of seventeen (17) years, and allowable renewals or reissues thereof.

I am aware that some of the materials and parts employed and utilized in the construction, arrangement and assembly of my invention are commonly known and employed to function generally and for purposes other than as utilized in my instant invention. Therefore, I do not claim as my own any such commonly known and available parts per se; on the contrary, I claim as my own only the use of such commonly known elements and parts as they perform the novel, collaborative and/or integral functions having

reference to my instant invention, in such instances and for such purposes for which they are essential to the aims and objectives and in accordance with the principles thereof as disclosed, described, illustrated and claimed.

Having reference to the claims I am aware that various possible changes and substitutions might be made in the construction, arrangement and assembly of the elements and parts without departing from the intent, spirit and scope of the claims hereinabove annexed, and in the methods, processes, procedures and sequences adopted to provide the execution and consummation of the embodiments involved, as well as in the employment and utilization of the component principles, elements, materials and parts embraced and involved in my invention as a whole.

Consequently it is to be understood that my claims are intended to be interpreted as illustrative and not to be limited in any sense to the exact and precise expressions given to the principles, elements, materials and parts therein embraced, embodied and involved.

On the contrary I deem my claims to specifically comprehend and to substantially involve, embrace, embody and include each and every principle, element and part disclosed and described, as well as each and every obvious apparent and contemplated purpose thereof.

My claims, further comprehend and include any and all possible variations of any of the circumscribed principles, elements and parts within the intent, spirit and scope of what is claimed, as well as any and all means, methods, processes, procedures and/or sequences of steps which may be employed, utilized and/or adopted to construct, arrange and assemble the embodiments involved in my invention as a whole.

Likewise my claims comprehend and include any and all possible contrivances within the intent, spirit and scope of what is claimed which may be employed individually, separately, together, collectively, integrally, cooperatively, reciprocally and/or collaboratively utilized in counterpart to perform the same functions of the principles, elements and parts disclosed and described, or in substitution thereof, to accomplish the aims, intents and purposes of my invention as a whole.

Specifically my claims comprehend, embrace, embody and include the construction, arrangement, assembly and integration of all the principles, elements and parts involved in the "peculiar structure" per se, as well as the applications, utilization, actuation and manipulation thereof in accordance with the purposes of my invention as a whole. It is intended that the employment and utilization of each of the component and integral principles, elements and parts shall be viewed and considered as a separate claim, as well as in the manner integrally related together in component, complemental, collaborative, corollary, cooperative and reciprocal combinations to achieve, attain, accomplish and consummate the aims, intents, objectives and purposes of my invention as a whole. Said "peculiar structure" may be constructed and/or processed either as one complete unit, or in separate parts, or in any combinations or prefabrications of suitable elements and parts which may be assembled into an integral whole within the intent, spirit and scope of what is claimed. Said "peculiar structure" has been more specifically described elsewhere herein.

Specifically my claims comprehend, embrace,

embody and include the arrangement and integration of the principle and element of "fulcrum" per se, as involved and employed in my instant invention, as well as the principle and element of "leverage and counter-leverage" thereby complementally and reciprocally created, generated and produced, by means of which to collaboratively accomplish and consummate the aims, intents, objectives and purposes of my invention as a whole. Said principles and elements of "fulcrum" and "leverage" have been more specifically described elsewhere herein.

Furthermore my claims in general comprehend and substantially embrace, embody and include any and all elements and parts, as well as any principles involved and embodied therein which may be created and/or produced within the intent, spirit and scope of what is claimed by those skilled in the arts of design and construction, and which may be substituted subsequent in my instant application for Letters Patent to serve the purposes of any of the principles, elements and parts embraced and embodied or involved in my instant invention; and including as well, within the intent, spirit and scope of what is claimed, any and all obvious and apparent evasions of any of the component principles, elements and parts which may possibly contribute to the requirements involved and embodied in my invention and which, whether innocently or otherwise conceive, may suggest themselves to nullify or otherwise infringe on the aims of my invention and my rights therein to the whole thereof.

In testimony that I claim as my own the foregoing invention as set forth in the claims herein I have hereunto affixed my signature this 18th day of September, 1943. Said invention has not been in public use or on sale in the United States nor in any country foreign to the United States, to my knowledge; the date immediately above represents the date of conception.

I claim:

1. In an artery compressor, the combination of a strap, a buckle permanently secured to said strap at one end of said strap, a rigid compressor element permanently attached to said strap, a rigid hook permanently attached to said strap, said compressor element being provided with an operating handle receivable in said hook, said hook being permanently attached to said strap at a point approximately midway between said buckle and said compressor element, said hook being adapted to receive said handle, said strap being adjustable as to effective length thereof by projecting an end thereof through said buckle and thereafter tightening said strap, the required compression being obtained by engaging said handle within the said hook preliminary to the adjusting of the effective length of said strap.

2. The combination set forth in claim 1, in which the compressor element is a cylinder and is attached to said strap along a generator of said cylinder, the said handle extending tangentially of said cylinder.

JOHN NUGENT WALTERS.
